UNITED STATES PATENT OFFICE.

LELAND SCOTT, OF ST. JOSEPH, MISSOURI, ASSIGNOR OF ONE-HALF TO LOUIS HUGGINS,
OF ST. JOSEPH, MISSOURI.

INTERNAL-COMBUSTION ENGINE.

1,103,089.

Specification of Letters Patent. Patented July 14, 1914.

Application filed October 22, 1912. Serial No. 727,193.

To all whom it may concern:

Be it known that I, LELAND SCOTT, a citizen of the United States, residing at St. Joseph, in the county of Buchanan and State of Missouri, have invented certain new and useful Improvements in Internal-Combustion Engines, of which the following is a specification.

My invention relates to internal combustion engines of the two-cycle type and has for one of its objects the provision of a fixed head within the cylinder and an inverted cup-shaped piston slidably mounted within the cylinder, the explosive mixture being supplied within the piston and compressed during the driven stroke of the piston and then supplied to the cylinder to be exploded in the next cycle of the engine.

Another object of my invention is the provision of a fresh air supply for driving out the burned gases after the explosive cycle prior to the admission of the explosive charge, said fresh air being under control of a valve operated by the crank shaft of the engine to open and close the valve at proper intervals for the correct operation of the engine.

My invention will be described in detail hereinafter and illustrated in the accompanying drawings, in which,

Figure 1 is a side view in elevation of an explosive engine constructed to conform with my invention; Fig. 2, a vertical sectional view through the center of the cylinder and crank case; and Fig. 3, a detail of the valve operating mechanism.

In the drawings similar reference characters will be used to designate corresponding parts throughout the several views.

My improved explosive engine comprises the crank case 1 within which is journaled the crank shaft 2 having the ordinary construction of crank arms 3 with the crank pin 4 on which is journaled one terminal of the piston rod 5.

The cylinder 6 of my improved engine is provided with the double wall construction ordinarily found in explosive engines to permit of the passage of water around the cylinder to keep it in a cool condition. The lower terminal of the cylinder 6 is extended into the crank case 1 as shown at 7 and is provided with a laterally extending flange 8 to which is secured the horizontal flange 9 of an inverted cup-shaped head 10 extending

upwardly into the cylinder, said cup-shaped head 10 being formed with vertical slots 11 for the purpose hereinafter stated.

Slidably mounted between the inner wall of the cylinder 6 and the outer wall of the head 10 is an inverted cup-shaped piston 12 that is pivotally connected as shown at 13 to the upper terminal of the piston rod 5 and said piston adapted to slide in the slots 11 of the head 10. The upper portion of the head 10 is provided with the ordinary packing 14 that engages the inner surface of the piston 12 and the upper portion of the piston 12 is provided with the packing 15 that engages the inner portion of the cylinder 6.

16 indicates an inlet port arranged in the side of the cylinder 6 and adapted to register at times with an opening 17 in the piston 12 to admit the explosive charge to the interior of the piston above the head 10, and 18 indicates the exhaust port communicating with said cylinder 6.

19 indicates a by-pass arranged in the casing of the cylinder 6 having its lower opening in substantial alinement with the inlet port 16, while its upper opening is alined with the lower portion of the exhaust port 18.

20 indicates a cover plate mounted on the cylinder 6 and covering the by-pass, said cover plate being held in position by means of a screw bolt 21 or other analogous structure.

22 indicates an air duct arranged in the casing of the cylinder 6 and communicating with the interior of said cylinder at a point just above the upper opening of the by-pass 19 and 23 an oscillating valve mounted in said fresh air duct, said valve being operated by means of an arm 24 secured to one end thereof and having pivotally secured thereto a link 25 that is operatively secured to a disk 26 rotatably mounted on the exterior of the crank case 1 and driven by means of a belt 27 or other suitable power mechanism from the crank shaft 2.

28 indicates a baffle extending from the upper end of the cylinder 12, and 29 a spark plug of any suitable structure for igniting the compressed charge in the ordinary manner.

30 indicates a port in the side of the piston 12 that registers at times with the lower opening of the by-pass 19 to permit of the passage of the explosive mixture from the interior of the piston 12 therefrom and

through said by-pass 19 into the upper portion of the cylinder 6.

In operation it will be apparent that when the piston 12 is moving in an upward direction to compress a charge within the cylinder 6, a partial vacuum will be created within said piston above the head 10 and when the opening 17 aligns with the inlet port 16, the explosive mixture will rush into the interior of said piston and fill it. Then when the explosive charge in the cylinder is fired to drive the piston 12 in a downward direction, the charge within the piston 12 will be compressed. As soon as the upper margin 15 of the piston 12 passes the orifice of the fresh air inlet 22 air will be admitted to the interior of the cylinder, the valve 23 being timed so that the fresh air duct 22 will be opened to admit the air and said air striking the baffle plate 28 will be directed upwardly and through the cylinder 6 to sweep the burned gases from the cylinder and out through the exhaust port 18. Then as soon as the upper margin of the piston 12 has 20 proceeded downwardly far enough to expose the upper opening of the by-pass 19, the opening 30 in the side of the piston will be in alignment with the lower opening to the by-pass 19 and the compressed charge within 25 the cylinder 12 will pass through said opening 30 and by-pass 19 into the cylinder 6 and complete the discharge of the burned 30

gases from the cylinder, the valve 23 in the meanwhile having been closed by the operation of the engine. Then when the piston 35 12 moves upwardly on another compression stroke, the operation heretofore described will be repeated.

Having thus described my invention what I claim is:—

In an explosive engine, a cylinder, a head rigidly mounted in the cylinder, an inverted cup-shaped piston slidably mounted between the cylinder and said head, and provided with apertures in the sides thereof, said cylinder being provided with an air duct, a valve rotatably mounted in the cylinder and controlling the passage of air through said air duct, said air duct being adapted to admit air to the cylinder to clean it of burned 45 gases and to cool it internally, means for actuating said valve, said cylinder being also provided with intake and exhaust ports in one of its sides, and by a by-pass opposite thereto, the intake port being adapted to 50 register with one of the apertures in the piston and the by-pass with the other.

In testimony whereof I affix my signature in presence of two witnesses.

LELAND SCOTT.
